Patented Oct. 17, 1922.

UNITED STATES PATENT OFFICE.

WILLIAM J. LOWE AND ANDREW SNEDDON, OF CHICAGO, ILLINOIS.

MILK-BOTTLE CLOSURE AND THE LIKE.

Application filed September 29, 1921. Serial No. 504,173.

To all whom it may concern:

Be it known that we, WILLIAM J. LOWE and ANDREW SNEDDON, both citizens of the United States, residing at Chicago, in the county of Cook and State of Illinois, have invented certain new and useful Improvements in Milk-Bottle Closures and the like, of which the following is a specification.

This invention has to do with an improved closure for milk bottles and the like. It has reference particularly to a removable closure for milk bottles which may be attached by the user in place of the ordinary paper cap or other closure on the bottle when the milk is delivered. The closure of the present invention may, however, be used to advantage for other purposes than the one just above mentioned.

One of the objects of the invention is to provide a closure which may be very easily attached to the upper portion of the bottle, and which when attached will close the bottle in a practically air tight manner. In this connection, another object is to provide a closure which may also be purposely removed from the bottle and be used over and over again on different bottles.

Another object of the invention is to provide a closure which is so constructed that it may also serve as a valve for permitting the discharge of the contents of the bottle under the convenient control of the user. In this connection, another object is to so arrange the parts that when the milk or other contents are being discharged they will flow through a spout so that their discharge may be conveniently directed.

Other objects and uses of the invention are to so arrange the closure that it will normally remain in closed and practically air tight condition, and to provide a closure which may very cheaply and easily be manufactured from stampings or other simple manufacturing processes.

Other objects and uses of the invention will appear from a detailed description of the same, which consists in the features of construction and combinations of parts hereinafter described and claimed.

In the drawing:

Figure 1 shows a fragmentary view of the upper portion of a bottle having applied thereto a closure embodying the features of the present invention;

Fig. 2 shows a vertical section corresponding to Fig. 1; and

Fig. 3 shows a plan view corresponding to Fig. 1.

Referring to the drawing, the closure is shown as being applied to the upper portion 60 of a milk bottle or the like 4. The upper portion of bottles of this class is generally enlarged as shown at 5 in Fig. 2 to provide a more or less distinct shoulder at the point 6. The inner portion of the neck is also 65 usually provided with a sill 7 on which the paper cap is initially seated. After removing this paper cap the closure of the present invention may be substituted.

The present closure includes a disk 8 of 70 sheet rubber or other suitable material having the elastic downwardly depending collar or flange portion 9 which preferably terminates in the lower beaded edge 10. The parts are so proportioned that the downwardly 75 depending portion 9 may be slipped down over the bulged portion 5 of the neck whereupon the bead 10 will snap under the shoulder 6 so as to retain the disk securely in place.

The disk 8 is provided with a perforation 11 of convenient size for the ready discharge of the contents of the bottle. This perforation is preferably in the form of a curved or arcuate slot as shown in Fig. 3. A disk shaped valve 12 seats up against the bottom face of the disk 8 and overlies the opening 11, so that when said disk 12 is raised into the position of Fig. 2 its edge portion will seat firmly against the bottom surface of the 90 rubber disk and hermetically close the opening 11. For this purpose, it is preferred that the disk 12 should be of concavo-convex form as shown in Fig. 2, so that its edge will seat before its body portion. A stem 95 13 is secured to the central portion of the disk 12, and is conveniently provided with a top button 14 which may be pressed down by the finger so as to force the valve 12 away from the disk 8. A spring 15 surrounding 100 the stem 13 retains the stem and valve normally in the raised closed position.

A metal disk 16 is preferably seated on top of the disk 8 so as to provide a convenient abutment for the lower end of the spring 15, and also to guide the stem 13 in its movements. Such disk 16 when used should preferably be of sufficient size to overlie at least a portion of the neck of the bottle itself as shown in Fig. 2. Such disk should also be 110 provided with a perforation 17 in registry with the perforation 11 of the disk. It is

also desirable when the disk 16 is used to turn its edge 18 upwardly away from the disk 8 so that the metal will not cut the rubber.

- 5 The disk 16 when used may also be provided with a spout 19 of convenient form and position to direct the flow of milk or other contents away from the opening. Such spout when used may be made as an integral 10 portion of the disk 16, the entire arrangement being stamped out from sheet metal.

It is observed that the spring 15 serves by pressing down against the disk 16 and by drawing the valve 12 upwardly to clamp the rubber disk 8 securely between the disk 16 and the valve. As soon as the button 14 is depressed to carry the valve away from the rubber disk, the pressure of the spring against the disk 18 is increased, so that the 20 parts are also kept in firm engagement with each other. It is also observed that with this arrangement it is possible to very thoroughly cleanse the entire device, since the disk 16 may be lifted away from the rubber 25 disk in order to permit water and other cleansing agent to freely enter between all of the disks.

While we have herein shown and described only a single embodiment of the features of our present invention, still we do not limit ourselves thereto except as we may do so in the claims.

We claim:

1. As a new article of manufacture, a closure for milk bottles and the like comprising in combination a rubber disk having a downwardly depending flange with a peripheral bead of size suitable to set down over the upper portion of the neck of the 40 bottle, there being an arcuate perforation in said disk, a sheet metal disk seated on top of said rubber disk and provided with an arcuate perforation and of size and location to register with the perforation of the rubber disk and being further provided with an upwardly and outwardly extending spout, a concavo-convex disk valve beneath the rubber disk with its concave side facing upwardly, a stem centrally secured to said 45 valve disk and extending up through the rubber disk and the top disk, and a spring surrounding said valve stem above the top disk and tending to draw the valve disk upwardly against the rubber disk and to force the top disk down against the rubber disk, substantially as described.

2. As a new article of manufacture, a closure for milk bottles and the like com-

prising in combination a rubber disk having a downwardly depending flange of size 60 suitable to set down over the upper portion of the bottle, there being a perforation in said disk, a sheet metal disk seated on top of said rubber disk and provided with a perforation of size and location to register 65 with the perforation of the rubber disk and being further provided with an upwardly and outwardly extending spout, a disk valve beneath the rubber disk, a stem secured to said valve disk extending up through the 70 rubber disk and the top disk and a spring surrounding said valve stem above the top disk and tending to draw the valve disk upwardly against the rubber disk and to force the top disk down against the rubber disk, 75 substantially as described.

3. As a new article of manufacture, a closure for milk bottles and the like comprising in combination a rubber disk having a downwardly depending flange with a peripheral bead of size suitable to set down over the upper portion of the neck of the bottle, there being a perforation in said disk, a sheet metal disk seated on top of said rubber disk and provided with a perforation of size and location to register with the perforation of the rubber disk, a disk valve beneath the rubber disk, a stem secured to said valve disk and extending up through the rubber disk and the top disk, and a 80 spring between the valve stem and the top disk tending to draw the valve disk upwardly against the rubber disk and to force the top disk down against the rubber disk, 85 substantially as described.

4. As a new article of manufacture, a closure for milk bottles and the like comprising in combination a sheet metal disk having an upwardly and outwardly extending spout, a rubber flange in conjunction 100 with the under face of said disk and underlying the peripheral portion of said disk and having a downwardly depending portion adapted to engage the upper portion of the neck of the bottle, there being a perforation in said disk, a disk valve beneath said disk and of proper size and contour to seat upwardly against the rubber flange portion underlying the disk, an upwardly extending stem secured to the disk valve and reaching upwardly through the disk, and a spring between said stem and the disk tending to draw the valve disk upwardly, substantially 105 as described.

WILLIAM J. LOWE.
ANDREW SNEDDON.
